UNITED STATES PATENT OFFICE.

CLAUD E. FULLER, OF NEW YORK, N. Y., ASSIGNOR TO NEW YORK BRICK HANDLING CORPORATION, OF NEW YORK, N. Y., A CORPORATION OF NEW YORK.

CONTINUOUS-BURNING HOOD.

Application filed October 1, 1925. Serial No. 59,841.

My present invention relates to brick machines, and more particularly to an improved continuous burning hood for use in the continuous burning of a kiln of brick in a wide kiln shed.

In the burning of kilns at the present day, particularly the burning of kilns in wide kiln sheds, the accepted method is to provide a structure running parallel with one side of the walls of the kiln sheds and on which structure is arranged one end of a plurality of parallelly arranged smoke hoods, the other end of such smoke hoods being secured to the side walls of the kiln shed and at the proper height. This method is not only expensive because of the amount of structure necessarily erected, but is also objectionable in that it prevents the free use of the kiln shed after a portion of the kiln has been burned, and also after the entire kiln has been burned and the bricks composing the same carted away. As is well known, in the continuous burning of kilns the sections of the kiln are fired at regular spaced intervals of time, and the burning of the kiln may be started before the end of the kiln is built up and, conversely, the latter portion of the kiln to be fired is in process of burning long after the bricks composing the first fired portion of the kiln have been removed. Because of the permanent structure necessary to be built in the kiln, it is extremely hard to manipulate cars or trucks and the consequence is that the production of brick and the efficient handling thereof is slowed down.

In my copending application, Serial No. 47,489, filed Aug. 1, 1925, I have shown and described an improved apparatus whereby the operation of the burning of a continuous kiln may be performed with the aid of a minimum amount of apparatus, such apparatus also employing the idea of smoke hoods, the smoke hoods being relatively fewer in number than the sections of the kiln and provision being made for gradually moving and erecting sections of supporting members from the burned sections of the kiln forward into association with the unburned sections. With the invention thus described in my copending application I am enabled to provide for the burning of a continuous kiln and also for the efficient handling of the brick during the erection of the sections and the removing of the

burned brick therefrom, leaving the major portion of the kiln free for the efficient handling of burned and unburned brick. My present invention is to be considered as an improvement over the invention described and claimed in my copending application above referred to, and, in my present invention, I provide a gantry crane structure carrying, as a permanent fixture and on the top thereof, a plurality of smoke hoods, the number of smoke hoods, however, being considerably less than the number of sections of kiln that may be built into a kiln shed, and also on such gantry crane structure I provide an improved means for supporting the kiln props on the gantry side. In carrying out this portion of my invention I provide a plurality of prop supporting means on the gantry side of the crane and associate therewith driving means which is, in turn, associated with the driving means for the gantry crane and which will enable the kiln props to move rearward relatively to, and at the same speed as, the forward movement of the gantry crane. Further, I provide in association with the smoke hoods a plurality of dampers operable from the floor of the kiln shed and which enables the dampers to be moved to the desired position for use when it is necessary to waste any water smoke that may be coming from the kiln or to let in cold air and temper down excessive hot air which may be coming from the kiln, or to act as a vent in case the exhaust fans are accidentally stopped during the period of time when a hood is over a hot kiln. The construction of the gantry is properly designed to support the weight of the smoke hood and to take a minimum of head room while at the same time keeping the lower members of the gantry at the proper distance above the hot kiln.

This is an important feature as it has been found that box-like hoods carried on beams, etc., close to the hot kiln are subject to excessive warping and, in case of the accidental stopping of the exhaust fan, are liable to collapse. As a hood in travelling over the tops of the kiln must have a certain clearance above the brick comprising such kiln, arrangements are provided for closing this clearance space during all times except when the gantry is travelling forward. In carrying out this feature of my invention I provide suitable shafting on all four sides

of the gantry to which are attached curtain shades, and the shafts are so mounted as to be operable by suitable levers.

The principal object of my invention, therefore, is an improved continuous burning hood.

Another object of my invention is an improved means for supporting a plurality of kiln props on a movable structure and maintaining said props stationary with respect to the kiln during the movement of the structure.

A further object of my invention is an improved damper means for continuous smoke hoods and means for operating the same.

A still further object of my invention is an improved means for closing the space between the top of the kiln and the lower surface or edge of a plurality of smoke hoods positioned over the kiln.

Other objects and novel features of the construction and arrangement of parts comprising my apparatus will appear as the description of the invention progresses.

In the accompanying drawings illustrating the preferred embodiment of my invention:—

Fig. 1 is an end elevation;

Fig. 2 is a side elevation;

Fig. 3 is a sectional plan view on the line 3—3 of Fig. 1, and

Fig. 4 is a fragmentary plan view of a portion of adjacent smoke hoods showing the dampers in position.

Referring to the drawings, 10 designates a kiln shed, the side wall 11 thereof being shown in elevation, and on the top of such side wall is shown a portion 12 of the usual roof structure. The kiln shed may be of any convenient width, and for ease in handling the brick it is customary to build the kilns of considerably less width than the width of the kiln shed. Such a kiln is shown at 13 in end elevation. The building of the kiln 13 of less width than the width of the kiln shed 10 necessitates the building of either a temporary or a permanent structure at the side of the kiln 13 remote from the side wall 11. Heretofore it has been customary to build such a structure in permanent form. The permanent form of structure, however, makes it difficult to handle expeditiously or economically the brick in the kiln, both during the building of the kiln and the subsequent tearing down of same for burning. In my present invention I have devised a structure consisting essentially of a rail 14, either permanently or temporarily set in the floor of the kiln shed and parallel to, but spaced apart from, the side wall 11 at any convenient distance. On such rail 14 run a plurality of flanged rollers 15 rotatably mounted in suitable bearings in the lower end of a structural iron framework 16 which forms the gantry end of a crane.

This framework 16 is of any suitable height, and to the top end thereof is secured a horizontal framework 17 which extends toward the side wall 11, such framework being provided on the end adjacent to the side walls 11 with downwardly extending members 18 to the lower end of which are rotatably mounted flanged wheels 19 rolling on a track 20 secured to the inner faces of the side wall 11. Mounted on the horizontal frame 17 and extending from the gantry frame members 16 are parallelly arranged smoke hoods 21. These smoke hoods extend from the gantry crane members 16 to a point adjacent to the side wall 11. Mounted on or in the wall 11 and extending transversely therethrough are a plurality of heat conduits 22, these conduits entering a conduit 23. The conduit 23 leads to any position where it is desired to use the excess heat arising from the burning of the kiln and ordinarily to a drying apparatus. The end of each of the smoke hoods 21 adjacent to the gantry crane members 16 are closed and the opposite ends are also provided with closures 24 which cooperate with the inner end of each of the conduits 22. The inner end of each of the conduits 23 is provided with a damper or closure 25 so that, when a smoke hood 21 is not in association therewith, the inner ends of the conduits 22 are closed by the member 25.

Each of the smoke hoods 21 on its top rounded surface is provided with a plurality of openings 26 and is also provided with tracks or grooves 27 spaced apart from each other and extending longitudinally of the smoke hoods throughout their length. In the tracks 27 are slidably mounted a plurality of damper plates 28, these plates 28 being connected in series to a cord or similar member 29 which extends at either end beyond the limits of the smoke hood, such ends passing over pulleys 30 rotatably mounted in suitable bearings on the gantry crane members 16 and the inner ends of the smoke hoods 21 respectively. The cord or similar member 29 makes it possible to operate the dampers 28 from the ground. The dampers 28 in association with the openings 26 are for use in wasting any water smoke that may be coming from the kiln or to let in cold air to temper down excessively hot air which may be coming from the kiln, or which acts as a vent in case the exhaust fans associated with the conduit 23 are accidentally stopped during the period when the smoke hoods 21 are over a hot kiln.

It is to be understood that the gantry crane members 16 form a structure that is considerably less in length than the length of the kiln shed or of the kiln 13 to be built therein, a typical installation having the gantry crane section of sufficient length to support on their top ends 12 smoke hoods 21 arranged side by side and parallel to each

other, while the kiln 13 may be six to fifteen times the length of such gantry crane members. There comes, then the question of properly supporting the kiln 13 against lateral expansion, and on the inner side of the crane, or the side of the crane adjacent to the side frame or wall 11 of the kiln this feature is provided for by associating with longitudinally extending members 31 and 32 secured to the inner face of the wall 11 and arranged parallel to each other the props 33, these props being preferably wedge-shaped, as shown in Fig. 1, as such a wedge will, by its own weight, "follow up" in the space between the members 31 and 32 and the side of the kiln 13 and keep tight. To provide for proper support on the outer side of the kiln 13 I preferably provide pairs of parallelly arranged members 35 on each side of the gantry crane members 16, such members 35 being substantially horizontal, as shown in Fig. 2. These members 35 act as supporting guides and tracks for rollers 36 rotatably mounted, top and bottom, to vertically arranged channel members 37. The channel members 37 are secured to parallelly arranged spaced endless chains 38, the spacing of the members 37 on such chains 38 being any desired. The top chain 38, as shown in Fig. 2, runs over a sprocket 39 secured to the upper end of a vertically arranged shaft 40 that is rotatably mounted in suitable bearings 41 on the right hand member 16 and also runs over a sprocket 42 secured to the upper end of a vertically arranged shaft 43 rotatably mounted in bearings 44 secured to the left hand member 16. The lower chain 38 runs over a sprocket 45 secured adjacent to the lower end of the vertical shaft 40 and also over a sprocket 46 secured adjacent to the left end of the vertical shaft 43. The sprockets above referred to are equal to each other in pitch and diameter so that each of the chains 38 runs at the same speed and in the same direction. Secured to the lower end of the shaft 40 is a bevel gear 47 which meshes with, and is driven by a bevel gear 48 of equal pitch and diameter secured to a shaft 49 that is rotatably mounted in a bearing 50 formed integral with the bearing member 41. Secured to the shaft 49 is a sprocket 51 over which runs a chain 52. This chain 52 also runs over a sprocket 53 secured to the shaft 55 of the right hand flanged wheel 15 shown in Fig. 2. The ratio of gearing and chain connecting the right hand flanged wheel 15 of the gantry to the parallelly arranged chains 38 is figured to give the same speed in both cases so that, as the gantry moves forward any given distance, the chain carrying the members 37 will move backward the same distance; that is, although the gantry moves forward, there is no relative movement of the members 37 opposite the side of the kiln

13 with respect to such kiln. This construction enables me to attach to the vertical members 37, as they come into position opposite the outer wall of the kiln 13, kiln props consisting of a base member 56 into which passes a screw 57, the hand wheel 58 being associated with said screw, and between the end of the screw 57 and the outer wall of the kiln 13 is a base pad 59. Only sufficient kiln props 33, 34 or 59 are furnished for the length of the gantry plus one extra, and as the gantry moves forward releasing the props in the burned end, they are carried ahead and attached to the side wall 11 or to the vertical members 37 respectively.

As the plurality of hoods 21, in travelling over the top of the kiln 13, must have a certain clearance above the top of the bricks, I provide on all four sides of the hoods suitable shafting 60 to which are attached curtain sheets 61, and by providing suitable means for rotating such shafts 60, the curtains 61 may be raised away from the top of the kiln 13 during the forward movement of the gantry and associated hoods.

With my improved invention only a relatively short gantry is required, such gantry extending only for a portion of the length of the kiln and being brought successively into association with the kiln as the burning of the same proceeds. It will be obvious, therefore, that, when no kiln is built in the shed, the gantry will occupy but a small portion of the shed and, further, when in position on a partially completed kiln, the kiln may be started burning in sections while the building of the remaining portion of the kiln proceeds, and, further, as the apparatus is moved along in the consecutive burning of the sections of the kiln, thus portions beyond which the gantry has passed will leave the burned kiln in position to be readily reached by trucks or other devices utilized in hauling away the burned brick.

While I have necessarily shown and described the preferred embodiment of my invention, somewhat in detail, it is to be understood that I may vary the size, shape, and arrangements of parts within wide limits without departing from the spirit of the invention.

Having thus described my invention, what I claim as new is:—

1. An improved smoke hood apparatus for kiln sheds and the like, comprising a plurality of parallelly arranged elements provided on their top surfaces with a plurality of openings, means for supporting said parallelly arranged smoke hoods above a kiln, and means for opening and closing said openings at will.

2. An improved smoke hood for use in the burning of kilns and the like, comprising a plurality of parallelly arranged smoke hood

- elements, means for supporting the same above a kiln to be burned, dampers arranged in the upper ends of said smoke hood elements, means for operating said dampers at will, and means for closing the space between the upper end of the kiln and the lower surface of the smoke hood elements.
3. An improved means for supporting the outer wall of a kiln against lateral expansion, comprising a rectangular plate-like wall, kiln props mounted on said wall and normally in engagement with the side wall of the kiln, and means for maintaining the kiln props stationary with respect to the side wall while permitting movement of the rectangular framework relative thereto.
4. An improved means for supporting the

outer wall of a kiln, comprising a gantry frame member substantially rectangular in shape and plate-like in form, vertical shafts 20 arranged at each end of said member, sprockets secured to said shafts, endless chains passing over such sprockets, vertically arranged bars secured to said chains, kiln props secured to said vertically mounted 25 bars, and means associated with said chains for permitting relative movement of the gantry crane members relative to the kiln wall while maintaining the kiln props stationary with respect to said wall. 30

In testimony whereof, I have signed my name to this specification.

CLAUD E. FULLER.
